NECK-TIE SUPPORT

Zenko Wada, Tokyo, Japan, assignor to
Seiwa Co., Ltd., Tokyo, Japan

Filed May 17, 1973, Ser. No. 361,220

Claims priority, application Japan Feb. 28, 1973

Term of patent 14 years

Int. Cl. D2—07

U.S. Cl. D2—359

FIG. 1

FIG. 2

FIG. 3

FIG. 4

FIG. 5

FIG. 6

FIG. 7

FIG. 1 is a front elevational view of a neck-tie support showing my new design;

FIG. 2 is a back elevational view thereof;

FIG. 3 is a plan view thereof;

FIG. 4 is a bottom plan view thereof;

FIG. 5 is a left side elevational view thereof;

FIG. 6 is a right side elevational view thereof;

FIG. 7 is a sectional view at VII—VII line of FIG. 2.

I claim:

The ornamental design for a neck-tie support, as shown.
